ROLLER SKATE

Frank J. Wagner, Franklin Square, N. Y., assignor of one-half to Carroll M. Bierman, Franklin Square, N. Y.; Elizabeth Wagner, administratrix of said Frank J. Wagner, deceased, assignor of one-half to Elizabeth Wagner

Application May 10, 1947, Serial No. 747,303

9 Claims. (Cl. 280—11.28)

1

This invention relates to roller skates in general and more particularly to the trucks of roller skates.

Among the objects of the present invention it is aimed to provide an improved roller skate having a pair of trucks, each of which has a single adjusting means to satisfy the taste of the skater depending to some extent upon his or her weight whereby the trucks may be adjusted not only to rock in a plane parallel to the shoe support, but also to incline to a line perpendicular to the shoe support as a result of the movement of the body of the skater so that the pairs of wheels of each truck will effectively engage the supporting floor and thereby assist a skater, particularly a figure skater, in a smooth and graceful execution of a predetermined figure or movement.

More specifically, the invention aims to provide an improved skate such as disclosed in application for patent filed March 19, 1946, Ser. No. 655,414, now Patent No. 2,490,849 dated December 13, 1949, which includes a shoe support, a pair of castings, each casting supporting one of the axles, a pair of pins, each fixed to said support and yieldably associated with one of said castings, a second pair of pins, each fixed to one of said castings, two ball connections rockably connected to said support, each ball connection being yieldably associated with one of said second pair of pins and one of said castings.

These and other features, capabilities and advantages of the present invention will appear from the subjoined detail description of one specific embodiment thereof illustrated in the accompanying drawings, in which

Fig. 1 is a plan view of a skate made according to the present invention.

Fig. 2 is a section on the line 2—2 of Fig. 1.

Fig. 3 is a front elevation of the embodiment illustrated in Fig. 1.

Fig. 4 is an enlarged section on the line 4—4 of Fig. 3.

Fig. 5 is a section on the line 5—5 of Fig. 4.

In the embodiment shown, there is illustrated a roller skate having a rear or heel plate 1 and a front or main plate 2 provided with suitable openings to facilitate securing a shoe thereto. These plates 1 and 2 in the present instance are mounted on the bar 3 which has two pairs of screw threaded openings, each pair, see Figs. 1 and 4, consisting of a large diameter opening 5, and a smaller diameter opening 6. The plates 1 and 2 and the bar 3 thus constitute the support for the shoe. The openings 5 in the present

instance both are disposed outwardly in a longitudinal direction relative to the openings 6. This skate is provided with two axles 7 and 8, the rear wheels 9 being journaled on the axle 7, and the front wheels 10 being journaled on the axle 8. Since the means for connecting the axles 7, 8 to the bar 3 are substantially identical, only one of them will be described in detail. This means or mechanism consists essentially of a casting 11 in which the axle, such as the axle 8, is journaled. This casting has an outermost screw threaded opening 12 to receive the end 13 of the pin 14 which has a collar 15 engaging the upper face of the casting 11. On the upper face of the collar 15 there is provided a rubber washer 16 to receive the lower face of the head 17 of the ball 18 constituting a guide, the pin 14 being slidably mounted in the chamber 19 formed in the ball 18. The ball 18 is rotatably mounted in the concave seat 20 formed in the bushing 21 having the diminished end 22 screw threadedly connected in the large opening 5 of the bar 3.

The casting 11 is also provided with a large opening 23 having a lower conical portion 24 and an upper annular recess 25 to receive the rubber buffer 26. The rubber buffer 26 is chambered to receive the shank 27 of the screw or pin 28 and has a lower conical portion to fit in the seat 24 and an upper cylindrical portion, the lower shoulder of which is located in the annular recess 25 in the casting 11. The upper part of the shank 27 of the screw 28 is screw threaded to receive the large adjusting nut 29, the locking nut 30 and the opening 6 in the bar 3. Preferably as shown, the upper cylindrical portion 31 of the rubber bushing 26 has a metal cap 32 positioned thereon with a central opening to permit the shank 27 to pass therefrom. Preferably also as shown, a wearing washer 33 is disposed between the cap 32 and the main adjusting nut 29, see Figs. 4 and 5. Preferably as shown in Figs. 4 and 5, one side of the shank 27 is flat, see the portion 34, to cooperate with the flat face 35 of the wearing washer 33. To assemble this mechanism, after the axle 8 has been fixed in the casting 11, the pin 14 may be screw threadedly connected thereto, until its collar 15 engages the upper face of the casting 11. Thereupon the rubber washer 16 is slipped over the pin 14, and then the ball 18 slipped on the pin 14 until its head 17 engages the washer 16. Thereupon the bushing 21 is connected to the bar 3.

Thereupon the rubber buffer 26 is positioned in the opening 23, as shown in Fig. 4, the cap 32 mounted on its upper end, the screw 28 then

positioned in the buffer 26, thereupon the washer 33 mounted on the shank 27, the nuts 29 and 30 screw threadedly connected to the shank 27, and then the ball 18 and shank 27 connected to the bushing 21 and bar 3, respectively, the ball 18 positioned in the seat 20 and the screw 28 screwed into the bar 3 until its upper end engages the plate 2. Thereupon the nut 30 is turned until it engages the lower face of the bar 3, and the adjusting nut 29 turned to effect the desired compression on the bushing 26.

The washer 33 due to the cooperation of the flat face 34 of the shank 27 with the flat face 35 of the washer 33, see Fig. 5, will be anchored against rotation with the adjusting nut 29, and consequently the cap 32 protected against wear when the adjusting nut 29 is turned to effect the desired compression of the buffer 26. The washer 33 will thus also serve as a lock nut to anchor the adjusting nut 29 against accidental displacement after it has once been turned for a predetermined adjustment.

From the foregoing it will thus be seen that for each truck or for each connecting means between the bar 3 and the axle 7 or 8, there is only one adjustable element, to wit, the nut 29. This nut 29 is provided to produce the desired compression as aforesaid on the buffer 26, which compression will vary depending upon the weight of the skater and the taste of the skater. In the use of a skate provided with this improved truck or connecting means, it will be seen that the rubber elements, to wit, the washers 16 and buffers 26, will at all times cushion the skater from the blow produced when the skate strikes the supporting floor. It will also appear that the balls 18 of the two trucks or connecting means will cooperate with the screws 27 constituting king pins to enable the axles of the two pairs of wheels 9 and 10 to incline relative to one another, see the dash and dot line position of the wheels 9 relative to the full line position of the wheels 10, when, as an instance, the skater executes a curve or turn, and that they will also cooperate with one another to enable the axles of the wheels 9 and 10 to incline relative to the plane of the plates 1 and 2, see the dash and dot line position of the wheels 10 in Fig. 3, when such turn or curve is executed.

It is obvious that various changes and modifications may be made to the details of construction without departing from the general spirit of the invention as set forth in the appended claims.

I claim:

1. In a roller skate, the combination of a shoe support including a bar, an axle for a pair of wheels, a casting in which said axle is mounted, a pair of pins, one pin fixed to said casting and the other pin fixed at a predetermined length to said bar and slideable relative to said casting, a bushing fixed to said bar, a ball device slidably mounted on said first pin and rotatably mounted in said bushing, yieldable means for said ball and said second pin to cushion the blow when the skate strikes the supporting floor in the course of use, and means for adjusting the yieldability of the yieldable means for said second pin.

2. A truck for a roller skate including a support for a shoe, a casting for the axle of a pair of wheels, a pair of pins, one pin fixed to said casting and the other pin fixed to said support and slideable in said casting, a bushing having a concave seat fixed to said support, a ball slidably mounted upon said first pin and rotatably mount-

ed in said seat, and yieldable means associated with said pins and casting to cushion the blow when the skate strikes the supporting floor in the course of use.

3. A truck for a roller skate including a support for a shoe, a casting for the axle of a pair of wheels, a pair of pins, one pin fixed to said casting and the other pin fixed to said support and slideable in said casting, a bushing having a concave seat fixed to said support, a ball slidably mounted upon said first pin and rotatably mounted in said seat, a yieldable buffer intermediate said second pin and said casting, an adjusting nut screw threadedly connected to said second pin and operatively associated to adjust the compression on said buffer, and a yieldable washer intermediate said ball and said casting.

4. A truck for a roller skate including a support for a shoe, a casting for the axle of a pair of wheels, a pair of pins, one pin fixed to said casting and having a collar disposed adjacent to said casting, the other pin fixed to said support and slideably mounted in said casting, a bushing including a ball and a head slidably mounted on said first pin, a second bushing having a concave seat fixed to said support, the ball rotatably mounted in said seat, a yieldable washer intermediate said collar and said head, a yieldable buffer intermediate said second pin and said casting, and an adjusting nut screw threadedly connected to said second pin and operatively associated to adjust the compression on said buffer.

5. A truck for a roller skate including a support for a shoe, a casting for the axle of a pair of wheels, a pair of pins, one pin fixed to said casting and having a collar disposed adjacent to said casting, the other pin fixed to said support and slideably mounted in said casting, a bushing including a ball and a head slidably mounted on said first pin, a second bushing having a concave seat fixed to said support, the ball rotatably mounted in said seat, a yieldable washer intermediate said collar and said head, a yieldable buffer intermediate said second pin and said casting, a cap on one end of said buffer, an adjusting nut screw threadedly connected to said second pin, and a wearing washer mounted on said second pin intermediate said adjusting nut and said cap and anchored against rotation, said nut being operable to predetermine the compression on said buffer.

6. In a roller skate, the combination including a pair of shoe supporting plates, a bar connecting the two plates to one another, a pair of castings, an axle for a pair of wheels mounted in each casting, a pair of pins for each casting, one pin of each pair of pins fixed to said casting, the other pin of each pair of pins fixed to said bar and slideable in said casting, a pair of bushings fixed to said bar and having concave seats, two guides, each including a ball and head slidably mounted on one of said first pins with its ball rotatably mounted in one of said seats, and yieldable means for each of said balls and each of said second pins to cushion the blow when the skate strikes the supporting floor in the course of use.

7. In a roller skate, the combination including a pair of shoe supporting plates, a bar connecting the two plates to one another, a pair of castings, an axle for a pair of wheels mounted in each casting, a pair of pins for each casting, the first pin of each pair of pins fixed to said casting, the second pin of each pair of pins fixed to said bar and slideable in said casting, a pair of bushings fixed to said bar and having concave

seats, two guides, each including a ball and head slidably mounted on one of said first pins with its ball rotatably mounted in one of said seats, and yieldable means for each of said balls and each of said second pins to cushion the blow when the skate strikes the supporting floor in the course of use, said first pins being disposed longitudinally outward of the skate relative to said second pins.

8. In a roller skate, the combination including a pair of shoe supporting plates, a bar connecting the two plates to one another, a pair of trucks, each truck including a casting, a pair of pins, one of said pins being fixed to said casting and the other of said pins being fixed to said bar and slidably mounted in said casting, a bushing including a concave seat fixed to said bar, a guide including a ball and head slidably mounted on said first pin, said first pin having a collar disposed adjacent to said casting, said ball being rotatably mounted in said seat, a yieldable washer intermediate said collar and said head, a yieldable buffer intermediate said second pin and said casting, a cap on one end of said buffer, an adjusting nut, and a wearing washer mounted on said second pin intermediate said cap and adjusting nut and anchored against rotation, said adjusting nut being adjustable to determine the compression on said buffer, said first pins being disposed longitudinally outward of the skate relative to said second pins.

9. In a roller skate, the combination including a pair of shoe supporting plates, a bar connecting the two plates to one another, a pair of trucks, each truck including a casting, a pair of pins,

the first of said pins being fixed to said casting and the second of said pins being fixed to said bar and slidably mounted in said casting, a bushing including a concave seat fixed to said bar, a guide including a ball and head slidably mounted on said first pin, said first pin having a collar disposed adjacent to said casting, said ball being rotatably mounted in said seat, a yieldable washer intermediate said collar and said head, a yieldable buffer intermediate said second pin and said casting, a cap on one end of said buffer, an adjusting nut, and a wearing washer mounted on said second pin intermediate said cap and adjusting nut and anchored against rotation, said adjusting nut being adjustable to determine the compression on said buffer, said first pins being disposed longitudinally outward of the skate relative to said second pins.
